UNITED STATES PATENT OFFICE.

FRANK YOKEL, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF PENNSYLVANIA.

DESIGN FOR A BOWL FOR LIGHTING-FIXTURES.

51,741.

Specification for Design.

Patented Feb. 5, 1918.

Application filed November 26, 1917. Serial No. 204,118. Term of patent 3½ years.

To all whom it may concern:

Be it known that I, FRANK YOKEL, a citizen of the United States, residing at Pittsburgh, in the county of Allegheny and State of Pennsylvania, have invented a new, original, and ornamental Design for a Bowl for Lighting-Fixtures, of which the following is a specification, reference being had to the accompanying drawings, forming part thereof.

Figure 1 is a top plan view illustrating my new design; and

Fig. 2 is a side elevational view of the same.

I claim:

The ornamental design for a bowl for lighting fixtures, as shown.

FRANK YOKEL.

Witnesses:

J. M. GEOGHEGAN,
LOIS WINEMAN.
